Primary Examiner — Kelley A Donnelly

(74) *Attorney, Agent, or Firm* — Steven R. Fairchild

(57) **CLAIM**

The ornamental design for a comic book display and storage, as shown and described.

DESCRIPTION

FIG. 1 is a perspective view of the comic book display and storage showing my new design with three partitions and filled with comic books.

FIG. 2 is a perspective view of the comic book display and storage showing my new design with three partitions and without any comic books.

FIG. 3 is a perspective view of the comic book display and storage showing my new design with two partitions and without any comic books; and,

FIG. 4 is a perspective view of the comic book display and storage showing my new design with one partition and without any comic books.

The broken lines showing the comic books within the comic book display and storage is for the purpose of illustrating context and form no part of the claimed design.

1 Claim, 4 Drawing Sheets
